CLAIM

The ornamental design for a soft sided luggage, as shown and described.

DESCRIPTION

FIG. 1 is a front perspective view of a soft sided luggage; FIG. 2 is a front view of a soft sided luggage; FIG. 3 is a rear view of a soft sided luggage; FIG. 4 is a left side view of a soft sided luggage; FIG. 5 is a right side view of a soft sided luggage; FIG. 6 is a top view of a soft sided luggage; and, FIG. 7 is a bottom view of a soft sided luggage. The broken lines and the unshaded areas within illustrate portions of the soft sided luggage and form no part of the claimed design.
